U.S. Appl. No. 29/382,719, filed Jan. 6, 2011, Huljak et al.

Primary Examiner — Thomas Johannes(57) **CLAIM**

The ornamental design for a bar soap and package, as shown and described.

DESCRIPTION

FIG. 1 is a perspective view of a bar soap and package embodying our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken line portion of the figure drawings is included to show unclaimed subject matter only and forms no part of the claimed design.
